UNITED STATES PATENT OFFICE.

GOTTHARD L. LOFSTROM, OF ROCKFORD, ILLINOIS.

SALT-SHAKER.

1,231,761.

Specification of Letters Patent.

Patented July 3, 1917.

Application filed July 31, 1916. Serial No. 112,372.

To all whom it may concern:

Be it known that I, GOTTHARD L. LOFSTROM, a citizen of Sweden, residing at Rockford, in the county of Winnebago and State of Illinois, have invented certain new and useful Improvements in Salt-Shakers, of which the following is a specification, reference being had to the accompanying drawings.

10 This invention comprehends certain new and useful improvements in kitchen and table articles, and relates particularly to salt shakers of the automatic anti-clogging type. The invention has for its primary object 15 an improved device of this character which will work effectively, by automatic means, to clear out the orifices in the top of the device when the shaker is set upright after each operation, the parts being so constructed 20 and arranged that they may be very cheaply manufactured and easily assembled and not liable to get out of order.

A further object of the invention is a device of the character above specified in 25 which the counterbalance for the orifice cleaning means may swing freely around in a relatively horizontal plane, so as to be thoroughly effective, no matter how the salt shaker is tipped, thereby always insuring 30 that the cleaning fingers or pins will be projected into and through the orifices in the top of the device when the shaker is restored to its normal position.

And the invention also aims to generally 35 improve devices of this class so as to render them more useful and commercially desirable.

With these and other objects in view, as 40 proceeds, the invention consists in certain constructions, arrangements and combinations of the parts that I shall hereinafter fully describe and claim.

For a full understanding of the invention 45 reference is to be had to the following description and accompanying drawing, in which—

Figure 1 is a vertical longitudinal sectional view of a salt shaker embodying the 50 improvements of my invention.

Fig. 2 is a similar view of a portion of the device in inverted position,

Fig. 3 is a horizontal section on the line 3—3 of Fig. 1, looking in the direction of 55 the darts,

Fig. 4 is a plan view of the top by itself, and

Fig. 5 is a plan view of a disk hereinafter specifically referred to.

Corresponding and like parts are referred to in the accompanying drawing and the following description by like reference characters.

Referring to the drawing, the numeral 1 designates the body portion of a salt shaker, 65 said body portion being of any desired construction, size, shape or design, as circumstances or judgment may dictate. 2 designates the top or lid of the device which may be detachably secured to the body portion 70 1 in any desired way as, for example, by the usual screw-thread connection 3 shown.

The top 2 is formed as usual with any desired number of orifices 4, through which the salt is shaken, and said orifices are designed to receive and accommodate pins 5, one for each orifice. These pins or cleaning fingers 5 are secured to or formed integral with a disk 6 which is mounted for a limited bodily movement within a casing 75 7 secured to the top 2 on the underside of the latter, and the casing is formed with any desired number of lateral recesses 8 of any desired size so as to permit of the flow of salt therefrom, so that it can find access 80 to the orifices 4 and pass freely through the latter. Preferably the casing 7 is formed on its bottom with any desired number of apertures 9 of any desired size and design, and the disk 6 is also formed with apertures 90 10 extending therethrough so that the salt may flow directly through the bottom of the casing and through the disk to find egress 85 through the orifices 4.

The disk 6 is provided with a stem 11 depending therefrom, and mounted for a longitudinal movement through the bottom of the casing 7 and through a cup or circular head 12 carried thereby, said head being formed with an annular flange 13 which is 100 engaged by the recessed intermediate portion 14 or fulcrum of a lever 15. The inner end of the lever 15 is pivotally connected, as at 16, to the stem 11, and the outer end of the lever carries a counterweight or balance 17, as shown.

From the foregoing description, in connection with the accompanying drawing, the operation of my improved automatic anti-clogging salt shaker will be apparent. In 110

the practical use of the device it is manifest that so long as the shaker assumes its normal upright position, the action of the weighted lever 15 will serve to hold the disk 6 in its uppermost position, with the pins 5 within and projecting through the orifices 4 whereby the orifices will be kept clean at all times and practically closed, so that moisture will be excluded from the interior of the shaker, 10 and as soon as the shaker is tilted over for the purpose of having the salt flow therefrom, the action of the lever will then be to withdraw the pins from the orifices, thereby permitting the salt to flow out through the latter, as desired. It will thus be seen that 15 I have prepared a very efficient construction of device of this character, and that the parts thereof may be very cheaply and easily assembled and not liable to get out of order. 20 Preferably guide rods 18 extend from the casing 7 to the top 2 and the disk 6 is formed with openings 18' through which the guide rods 18 extend, whereby the proper movements of the disk will always be insured. 25 Preferably also the weight 17 is substantially of crescent shape with pointed ends 17' whereby it will serve to cut up and loosen the salt in the shaker as it swings around. The object in so mounting the 30 weighted lever that it is capable of swinging around the stem 11, as on a center, is that thereby the weight is always disposed at the lowest portion of the salt shaker when the latter is tipped. Thus for instance if the 35 shaker, as illustrated in Fig. 1, is tipped in a plane at right angles to the plane of the section, the weight will automatically swing to the lowest point of the shaker and be in position to operate immediately that the 40 shaker is fully tipped. Furthermore, inasmuch as the weight is capable of swinging around the axis formed by the stem 11, the weight acts to break up agglomerated salt and prevent packing of the salt so that the 45 salt will pass freely through the openings in the casing and the openings in the plate 6.

While the accompanying drawing illustrates what I believe to be the preferred embodiment of my invention, it is to be understood that the invention is not limited thereto but that various changes may be made in the details of construction, arrangements and proportions of the parts without departing from the scope of the invention as 55 claimed.

What is claimed, is:

1. A salt shaker provided in its top with orifices, and with a casing below the top, a disk movable in said casing and provided 60 with pins adapted to extend into the orifices for the purpose specified, a stem carried by said disk and movable through the casing, the casing being provided with a head depending therefrom, and a weighted lever 65 fulcrumed on said head and pivotally con-

nected to said stem, as and for the purpose set forth.

2. A salt shaker provided in its top with orifices, and with a casing below the top, a disk movable in said casing and provided 70 with pins adapted to extend into the orifices for the purpose specified, a stem carried by said disk and movable through the casing, the casing being provided with a head depending therefrom, the head being formed 75 with an annular flange, and a weighted lever provided intermediate of its ends with a freely sliding connection with said flange and pivotally connected at one end to said stem.

3. In a salt shaker, the combination of a top formed with orifices, a disk provided with pins and movable in a direction to project said pins into said orifices, said disk being provided with a stem, a fulcrum, and a lever engaging said stem and freely shiftable upon said fulcrum, as and for the purpose set forth.

4. A salt shaker provided in its top with orifices and with a casing secured to the underside of the top, a disk movable in said casing and provided with pins adapted to extend into the orifices, for the purpose specified, a stem carried by said disk and movable through the casing, the casing being provided with a head depending therefrom, the head being formed with an annular flange, and a weighted lever provided intermediate of its ends with a freely sliding connection with said flange, and pivotally connected at one end to said stem, the casing being formed in its sides and bottom with openings extending therethrough, and the disk being formed also with openings extending therethrough.

5. In a salt shaker, the combination of a top provided with orifices, a disk provided with pins and movable in a direction to project said pins into said orifices, and a lever operatively connected to said disk and provided with a counterbalancing weight, for the purpose specified, said lever being capable of swinging around in the shaker and formed with pointed ends.

6. In a salt shaker, a perforated closure, a 115 member disposed within the shaker and having pins registering with the perforations of the closure, said member being movable in a direction to project said pins into the perforations, and a lever disposed entirely within the shaker having its inner end operatively engaged with the member, having its outer end weighted, and fulcrumed intermediate its ends.

7. A salt shaker having a perforated closure and cleaning means disposed within the shaker and automatically urged into the perforations when the shaker is right side up but urged out of said perforations when the shaker is inverted, said cleaning means in 130

cluding a weighted member projecting laterally from and rotatable around the longitudinal axis of the shaker and acting to break up agglomerated salt adjacent the 5 mouth of the shaker.

8. A salt shaker having a perforated closure, a cleaning member having pins registering with the perforations in the closure, said cleaning member being movable toward 10 or from the closure, and weight actuated means for urging the cleaning member toward the closure when the shaker is right side up but urging the cleaning means away from the closure when the shaker is inverted, 15 said weight actuated means being mounted for movement parallel to the axis of the shaker to operate said cleaning member and for free rotary movement in a plane at right angles to the axis whereby the weight may 20 swing to the lowest portion of the shaker when the latter is tipped.

9. In a salt shaker, a perforated closure, a casing plate mounted upon the closure but spaced from the inside face thereof, and 25 formed with a plurality of openings to permit the passage of salt therethrough, a

cleaning disk disposed between the casing plate and the closure and having a plurality of pins registering with the perforations in the closure, said disk being movable toward 30 the casing plate to retract the pins from the perforations, and means urging said disk toward the closure when the shaker is right side up but urging said disk toward the casing plate and retracting the pins from the 35 perforations in the closure when the shaker is inverted.

10. A salt cellar having a perforated closure, a fixed stem projecting inward from the inner face of the closure, and means for 40 breaking up agglomerated salt comprising a radially projecting arm having a weight at its outer end, said arm being operatively mounted on the stem for movement around the axis of the stem. 45

In testimony whereof I hereunto affix my signature in the presence of two witnesses.
